UNITED STATES PATENT OFFICE

GEORGE GOODLINE, OF PAWTUCKET, RHODE ISLAND.

SHEDDING MECHANISM FOR LOOMS.

1,116,814.

Specification of Letters Patent. Patented Nov. 10, 1914.

Application filed July 11, 1913. Serial No. 778,537.

To all whom it may concern:

Be it known that I, GEORGE GOODLINE, a citizen of the United States, residing at Pawtucket, in the county of Providence and State of Rhode Island, have invented certain new and useful Improvements in Sheding Mechanisms for Looms, of which the following is a specification.

This invention relates to shedding mechanisms for looms and particularly to such mechanisms when adapted for use in plain weaving where the warp includes a large number of ends or threads, in which case it is usual to employ two or more harnesses in each set for want of room in a single harness for all the threads which go to form each sheet or half of the shed. Ordinarily the two sets of harnesses pass each other *en masse* in a horizontal plane, which, especially in view of the additional crowding due to the existence of the heddles immediately supporting the ends, obviously produces considerable wear on the ends, particularly if the warp is soft; this condition is augmented by the presence of knots in the warp, while, due to loose ends or other imperfections, it frequently causes the ends to become bound together so that they cannot pass through the dents of the reed without becoming broken. The harnesses of each set furthermore usually have the same extent of throw (rise or fall); that is, notwithstanding the fact that the sheds converge forwardly toward the finished goods, the extents of movement of the several harnesses are not relatively such as to make allowance for such convergence in the sheds, in consequence of which the threads at the forward part of each sheet of the shed are not all in a single plane: The advantages of having all the threads in the forward part of each sheet of the shed in the same plane, such as affording greater room for the shuttle and avoiding unequal strains on the warp ends, will be at once apparent to any weaver.

The object of this invention is so to construct a shedding mechanism for looms for use in plain weaving and including in each set a plurality of harnesses that during the changing of the sheds the warp ends of said sheets shall be so moved or operated that comparatively few of said ends will pass each other in the same horizontal plane simultaneously and the crowding of the warp ends in passing and the resultant wear or entanglement thereof will be avoided.

Another object of this invention is so to construct a shedding mechanism for looms for use in plain weaving and including in each set a plurality of harnesses that, whereas at the completion of a shed all the warp ends in each sheet thereof shall be coincident with a single plane with respect to the forward part of such sheet, during the changing of the sheds the warp ends of said sheets shall be so moved or operated that comparatively few of said ends will pass each other in the same horizontal plane simultaneously and the crowding of the warp ends in passing and the resultant wear or entanglement thereof will be avoided.

Other objects of the invention will appear in the following description.

In the accompanying drawing, wherein the invention is fully illustrated, Figure 1 is a front elevation, partly diagrammatic and partly in section, of a loom provided with the improved shedding mechanism arranged for "skip-shaft-draw"; Fig. 2 is a plan view of the actuators, the shaft carrying them and a part of the means for rocking said shaft; Fig. 3 is a side elevation of what is shown in Fig. 1; Fig. 4 is an end elevation of one of the sets of actuators; Fig. 5 is a plan view of one of the sets of actuators where there is an odd number of harnesses to a set and the harness is arranged in "skip-shaft-draw"; Fig. 5^a is a diagram of the harness and warp operated by the actuators in Fig. 5; Figs. 6 to 10 are diagrammatic views illustrating the manner of changing a shed in accordance with the present invention, the harness having an even number to a set and arranged in "skip-shaft-draw" and the actuators here appearing suitably separated for the sake of clearness in illustration; Figs. 6^a to 10^a are diagrammatic views similar to Figs. 6 to 10, illustrating the manner of changing a shed where the harness is arranged in "straight-over-draw"; Fig. 11 illustrates my invention where eight eccentric actuators are employed; Figs. 12 and 13 are diagrammatic views illustrating the two common arrangements of the harnesses and warp, that is in "skip-shaft-draw" (i. e., where the warps are passed through the harnesses alternately); and in "straight-over-draw" (i. e., where the warps are passed through the harnesses in regular succession); and Fig. 14 is a plan view of a set of ten actuators for a harness arranged in "straight-over-draw."

In the loom frame a is journaled the horizontal rock shaft b . Formed in part with or mounted on said shaft is one or more series of actuators—in the present case, two such series being shown, they being substantial counterparts of each other. These actuators in the present instance are in the form of eccentrics, being designated (referring first to Figs. 6 to 10) c, d, e and f . Around the periphery of each actuator and suitably attached thereto, as by the screw x , is a strap or other flexible device c', d', e', f' , the same appearing simply as lines on Fig. 1 to avoid confusion. In the present instance the loom illustrated has four harnesses, c'', d'', e'', f'' , to which the straps c', d', e', f' are respectively connected in a manner to be explained.

Assuming for the meanwhile that the several harnesses are suitably suspended while being reciprocated vertically from the actuators, the disposition and relation of the several eccentrics, straps and harnesses are substantially as follows: One half of the eccentrics, (say c and e), are set on the shaft reversely to the other half. The straps for the first and second harnesses (counting from rear to front in Fig. 3) pass at one side of the shaft b around two reversely set eccentrics (as c, d) while the straps for the third and fourth harnesses pass at the other side of the shaft around the remaining two reversely set eccentrics (as e, f). The several eccentrics, moreover, are gradually reduced in diameter, eccentric c being the largest and eccentric f the smallest, as clearly shown in Fig. 1.

Now on a view to Figs. 6 to 10, inclusive, (illustrative of the invention in connection with "skip-shaft-draw") it will be seen: First, that in the rocking of the shaft b , due to the gradual reduction in the diameter of the eccentric, the several harnesses from rear to front in Fig. 1 will have imparted to them movements which gradually reduce in extent. That is to say, if the rearmost harness has a movement of a given extent, the second harness from the rear will have a somewhat less movement; the third harness still less movement, and the fourth harness the least movement. In this way, each time a shed is formed, the front portion of each sheet thereof forms a perfect plane, resulting in uniform strain on the warp ends, greater room for the shuttle and other advantages which will be at once apparent to the weaver. Second, it will be seen that in the rotation of each eccentric (the shaft moving at a constant speed) the delivery or winding up, as the case may be, of the corresponding straps will be alternately fast and slow. This, in view of the stated arrangement of the several straps relatively to the eccentrics, will result, during the changing of a shed, in the warp ends passing each

other in the order substantially as illustrated in Figs. 7 to 9. Thus, in Fig. 7 the threads appertaining to the harnesses d'' and e'' are passing each other; in Fig. 8 the threads appertaining to the harnesses d'' and f'' are passing each other at one point while the threads appertaining to the harnesses c'' and e'' are passing each other at another point; and in Fig. 9 the threads appertaining to the harnesses c'' and f'' are passing each other. In Fig. 10 the new shed is shown as completed. In short, the eccentrics and straps afford means to oppositely move both sets of harnesses, the harnesses of each set in sequence, and bring the harnesses thereof all periodically to rest in positions where the warp supporting portions (as the thread-eyes y) of each set of harnesses coincide with one of two planes converging forwardly toward the cloth.

In Figs. 6^a to 10^a, inclusive, (illustrative of the invention in connection with "straight-over-draw"), where eccentrics c and d are set on the shaft reversely to eccentrics e and f , and the straps for the first and second harnesses (counting from front to rear in Fig. 2) pass around opposite sides of eccentrics c and d , while the straps for the third and fourth harnesses pass around opposite sides of eccentrics e and f , it will be seen, first, that inasmuch as the eccentrics c, d, e, f are gradually reduced in diameter, each time the shed is formed the front portion of each sheet thereof will form a perfect plane converging toward the front portion of the other sheet, the same as in Figs. 6 to 10; second that, during the changing of a shed the threads appertaining to harnesses d'' and e'' will first pass each other (Fig. 7^a); that then the threads appertaining to the harnesses c'' and d'' on the one hand and e'' and f'' on the other hand will pass each other (Fig. 8^a); that then the threads appertaining to the harnesses c'' and f'' will pass each other (Fig. 9^a); and then finally the threads appertaining to the harnesses c'' and e'' will be in one sheet of the shed and the other two threads in the other sheet of the shed (Fig. 10^a), having reversed their positions.

In the previous description I have referred only to the simplest type of a shedding mechanism of the kind to which my invention relates, that is, one in which there are only two harnesses to a set. It may be stated at this point that if in the case of either "skip-draft" or "straight-over" draw there are an odd number of harnesses to a set it is necessary that two of the actuators, one for a harness of each set, be concentric, as the actuators g, g' in Fig. 5, their straps extending at opposite sides of the shaft b , that is reversely around them; in either case, if there are an even number of harnesses to a set all the actuators should be eccentrics.

(That, moreover, in the case of "skip-shaft-draw", it is necessary, on increasing the harnesses to a number above four and in the case where each half or set would have an 5 odd number of harnesses, to arrange the straps, not so that there would be in every instance a complete pair at either side of the shaft, but so that there would be an odd strap on one side of the shaft at one end of 10 the series of eccentrics and another odd strap at the other side of the shaft at the other end of the series, for otherwise—compare Figs. 5 and 5^a—numbers 1 and 2 warp threads, for instance, would rise and fall 15 together, instead of in opposite directions). The necessity for providing the concentrics is due to the fact that in general, where 20 actuators are added to the original four, if the actuators be simply different in size and 25 not so that their centers are relatively different from those of the original actuators it will be found that the harnesses which they control will be passing in coincidence with the harnesses controlled by actuators corresponding to them in the first four, so that, 30 in short, the desired crossing in sequence, throughout, would not occur.

It has already been indicated that when 35 actuators are added to the original four it is necessary to change the centers of the added actuators relatively to those of the original actuators. When actuators are added in the case where the harnesses are arranged in two sets each having an even number of harnesses 40 all the actuators should be eccentrics, and in such cases each multiple of added actuators should have greater eccentricity than the preceding multiple. This is shown in Fig. 11, where the four right-hand actuators are 45 set in greater eccentricity than the remaining four, all being eccentrics. In practice, if the eccentricity of the left hand four in Fig. 11 is say one-fourth of an inch the eccentricity of the right hand four would be 50 about one-half of an inch.

Fig. 14 shows a system of actuators to be used in connection with a harness arranged for straight-over-draw and containing ten harnesses. It will thus be seen that when 55 adding actuators for use in harness arranged for straight-over-draw the straps for the added actuators are related throughout thereto the same as the original four actuators.

Any suitable means, suitably connected 60 with the harness to coöperate with the actuators in properly supporting the harness, may be employed, but I prefer to use the system of rotary devices *h*, *i*, *j*, *k* shown in Fig. 1 as substantial counterparts of the actuators and having straps *h'*, *i'*, *j'*, *k'* extending around and attached to their peripheries in the same relation as the straps *c*, *d*, *e*, *f* extend around the actuators *c*, 65 *d*, *e*, *f*.

Any suitable means for rocking the shaft *b* may be utilized, but I prefer to use that shown in Figs. 1 and 3 because the same has been designed with the particular purpose of affording a dwell after the rotation of 70 said shaft in each direction, necessary upon the completion of a shed to give the shuttle time to complete its flight through the shed before the shed is changed.

The shaft *b* carries pulley *l* around 75 which, reversely, extend the straps *m*, attached thereto and also attached to the bow-shaped lower end of a lever *n* pivotally suspended in the frame *a*. To this lever is attached one end of a link *o*, the 80 other end of which is pivoted to one of two elliptical gears *p*, *q*, suitably journaled in the frame, the gear *q* being preferably carried by the cam shaft *r* which may be driven in any suitable manner. The gears are 85 related to each other in a well known manner, so that an alternately slow and fast motion is imparted to the gear *p* when rotated by the gear *q*, and this motion, when transmitted through the link *o*, lever *n*, 90 straps *m* and pulley *l* to shaft *b* produces the desired periodic dwell in the operation of the harness.

Having thus fully described my invention, what I claim as new and desire to secure by 95 Letters Patent is:—

1. A shedding mechanism for looms including two sets of movable harnesses, and means for actuating the harnesses at different speeds including oscillatory eccentric actuators eccentric in different degree. 100

2. A shedding mechanism for looms including two sets of movable harnesses, and means for actuating the harnesses at different speeds including oscillatory eccentric actuators having different diameters and being eccentric in different degree. 105

3. In combination, harnesses arranged in succession longitudinally of the warp and divided into two sets of a plurality of harnesses to a set, each set being reciprocally movable from a position where its warp-supporting portions coincide with one of two planes converging forwardly toward the cloth to a position where its said warp-supporting portions coincide with the other of said planes, and means to oppositely move both sets, the harnesses of each set in relatively progressive disposition and bring the harnesses thereof all simultaneously to 110 rest in said positions. 115

4. In combination, harnesses arranged in succession longitudinally of the warp and divided into two sets of a plurality of harnesses to a set, each set being reciprocally movable from a position where its warp-supporting portions coincide with one of two planes converging forwardly toward the cloth to a position where its said warp-supporting portions coincide with the other of 120 125 130

said planes, and means to oppositely move both sets, the harnesses of each set at different relative speeds, and bring the harnesses thereof all simultaneously to rest in said positions.

5. In combination, harnesses arranged in succession longitudinally of the warp and divided into two sets of an odd number of harnesses to a set, and means to oppositely move both sets, the harnesses of each set in relatively progressive disposition, including two sets of rotary actuators each comprising a concentric actuator and a plurality of eccentric actuators and operative connecting means between the respective harnesses of both sets and all the actuators.

6. In combination, harnesses arranged in succession longitudinally of the warp and divided into two sets of an odd number of harnesses to a set, and means to oppositely move both sets, the harnesses of each set at

different relative speeds, including two sets of rotary actuators each comprising a concentric actuator and a plurality of eccentric actuators and operative connecting means between the respective harnesses of both sets and all the actuators. 25

7. A shedding mechanism for looms comprising two sets of movable harnesses each including at least four harnesses to a set, 30 eccentric actuators mounted to oscillate and corresponding in number to said harnesses, some of said actuators being eccentric in a different degree from that of others, and means operated by said actuators for moving said harnesses. 35

In testimony whereof I affix my signature in presence of two witnesses.

GEORGE GOODLINE.
